STEAM-ACCUMULATOR PLANT.

Application filed January 23, 1925. Serial No. 4,343.

To all whom it may concern:

Be it known that we, JOHANNES KARL RUTHS and NILS PERSSON, subjects of the King of Sweden, and residing in Djursholm, Sweden, and Stockholm, Sweden, respectively, have invented certain new and useful Improvements in Steam-Accumulator Plants, of which the following is a specification.

10 Our invention relates to steam plants wherein steam is bled from steam consumers and more particularly to steam plants equipped with accumulators.

Our invention also relates to steam plants 15 wherein power machinery, especially turbines, operates in conjunction with a steam accumulator and one object of the invention is to obtain a greater pressure drop than has hereto been possible in such power machinery, thereby obtaining a greater amount 20 of work from process steam whereby the cost of power is diminished and plant efficiency increased.

Our invention further has for its object 25 to provide a steam accumulator plant, wherein the back pressure or the extraction pressure of steam consumers, for example power machinery, such as turbines, is made independent of variations in the pressure 30 prevailing in an accumulator.

Previously known plants equipped with accumulators and in which steam is passed 35 through a consumer such as a motor, for example, a turbine or a reciprocating engine in which power is extracted have been so arranged that the back pressure or extraction pressure of the consumer, that is to say, that pressure to which the steam for the low 40 pressure consumers expands in the motor, is either always higher than the highest accumulator pressure, or substantially the same as that pressure, and variable therewith.

Both these conditions are objectionable in 45 that in the first case all the available power is not extracted from the steam and in the second case, where the extraction pressure is substantially the same and varies with the pressure in the accumulator, that the work-

ing of a consumer is hampered and the amount of power extracted in a motor is a function of the variable pressure in the accumulator.

It is evident also that when the back pressure of a motor varies continually in accordance with variations in the accumulator, that the regulation of the motor is difficult and as smooth an operation will not be obtained as when the back pressure is constant.

In some instances it has been found, particularly in plants which use a large amount of low pressure steam and in which the peaks are relatively small as compared to the average steam consumption, that it is possible to extract a greater amount of power from process steam if this steam in a quantity up to that available in the high pressure line, can expand in the motor from the high pressure of the line from which it is taken all the way down to the pressure at which the steam is eventually used for process work and have this complete expansion irrespective of variations occurring in accumulator pressure while the surplus of steam generated over the momentary consumption is led in a path parallel to the path of steam passing through the motor to the accumulator from which steam is led to low pressure consumers when the demand of these consumers is greater than the supply afforded by the motor.

The present invention provides means whereby the greater extraction of power in the motor as above outlined is accomplished and, further, obtains this result by means of a simplified arrangement of regulating elements. As pointed out in our co-pending application Serial No. 574,089 filed July 10th, 1922, to which this application is to be considered as relating back for all common subject matter, and in which the present invention is disclosed, the majority of plants wherein the pressure in the motor drops all the way from the high pressure to the low pressure lines a regulating mechanism is necessary wherein the regulation is a function of the pressure before and behind the motor. In the application referred

to most of the arrangements described have a minimum of four regulating elements; one to control the flow of steam into the motor, one to control the flow of steam from the motor, one to control the flow of steam through a line connecting the boilers with the accumulator in parallel with the motor, and a reducing valve placed between the accumulator and the low pressure consumers 10 and so arranged that the said reducing valve also lies between the accumulator and the point of connection of the extraction or back pressure line to the low pressure line. In the present invention the arrangement is 15 simplified by causing the pressure behind the motor to operate the valve in the parallelly disposed steam line in such a manner that one of the regulating elements controlling the flow through the turbine can be 20 omitted. The invention will be described more fully in connection with the accompanying drawings in which:

Fig. 1 shows a plant according to the present invention provided with a back 25 pressure turbine and without high pressure consumers;

Fig. 2 shows a plant similar to Fig. 1 except that high pressure consumers are supplied with steam directly from the boiler;

Fig. 3 shows a plant comprising a single extraction turbine;

Fig. 4 shows a plant comprising a double extraction turbine and also having other regulating arrangements of use in certain 35 plants, and

Fig. 5 is a section taken partly on line 5-5, Fig. 4.

Referring to Fig. 1, 10 represents a steam generator, from which steam is conducted 40 through the conduit 11, partly through conduit 12 to the motor 13 which may be a turbine, and, as illustrated, driving a generator 14 connected with the electric circuit 15, to supply power thereto, and 45 operating in parallel with a second electric generator 16, driven for example by a water turbine the arrangement being such that the power generated in the motor 13, can under normal conditions all be transferred 50 into electrical energy in the generator 14 and utilized in the circuit 15. The steam after passing through the motor 13 is conducted 55 through the back pressure connection 17 to low pressure conduit 18 from which steam is supplied to low pressure consumers 19 which may be dryers, heaters, or any other consumers using low pressure steam.

Another part of the steam generated is 60 conducted through conduit 20 in parallel to the motor and is delivered to the accumulator conduit 21 to which an accumulator 22 is connected, preferably, in parallel to conduit 21. 23 and 24 designate check valves 65 which control the flow of steam into and

out of the accumulator in known manner. A reducing valve 25 is placed between accumulator conduit 21 and low pressure conduit 18 and controls the flow of steam from the accumulator conduit to the low pressure conduit. This reducing valve is so placed that steam can expand in the motor all the way down to the pressure in conduit 18, that is, the connection between back pressure conduit 17 and conduit 18 is made 70 at a point which is behind the reducing valve 25. In other words, reducing valve 25 is placed between the accumulator and the point of connection of the back pressure line to the low pressure conduit of the steam 80 plant.

With this arrangement it is evident that in order to prevent more steam from passing through the motor than is needed in the low pressure line a regulation must be supplied 85 which will limit the amount of steam passing through the motor. That is, the motor might at certain times suck in more steam than the low pressure consumers need in which case the flow of steam through the 90 motor must be limited. This regulation is accomplished in the following manner:

A valve 26 is provided in the conduit 20 and is controlled by the pressure in conduit 17 in such a manner that an increase of 95 pressure tends to open the valve and a decrease of pressure tends to close the same. This valve opens when the pressure in conduit 17, and consequently conduit 18, increases above a predetermined value and 100 closes when the pressure falls below a predetermined value. This valve alone, however, would not properly regulate the flow of steam to and past the motor but it is also necessary to have the valve 27 in conduit 12 which controls the flow of steam to the motor. Valve 27 is also a pressure responsive valve. It opens when the actuating pressure has risen above a predetermined value and closes when the pressure has fallen below a predetermined value. Between these two predetermined values it increases the steam flow to the motor upon a rise of pressure in front of the same and decreases the flow when the steam pressure falls. 110 Such a valve may be termed an "overflow valve".

The operation of the plant is as follows: Suppose the pressure in conduit 18 rises, due either to decreased consumption in the 115 low pressure consumers or an increase of steam quantity passing through the turbine. The rise of pressure causes valve 26 to open somewhat, thereby allowing a greater flow of steam through conduit 20. This increase of flow through conduit 20 causes a drop of pressure in conduit 18 thus returning the plant to a state of equilibrium.

Suppose the pressure in conduit 18 decreases due for example to increased con- 130

sumption of consumers 19. The consequent decrease of pressure causes a closing of valve 26 which in turn increases the pressure in conduit 11, thereby causing an opening of valve 27 so that more steam passes through the motor. If, despite this increased supply of steam from the motor to the low pressure line, the quantity of steam supplied to the low pressure consumers is insufficient as indicated by low pressure in conduit 18, valve 25 opens and steam passes from the accumulator to the low pressure line.

Suppose the pressure in conduit 11 increases. This causes an increased flow of steam through valve 27, thereby causing a greater flow through the motor to the low pressure line 18. Should the supply of steam to the low pressure consumers then be greater than what is needed the pressure would rise in conduit 18 and valve 26 will open more or less in turn causing valve 27 to be closed more or less, whereby less steam is passed through the motor and a greater quantity by-passed to the accumulator.

Although only a few possibilities in pressure changes in the plant, and the consequent reaction of the plant have been pointed out, it is clear that the regulation will take care of any conditions and that a constant pressure can be obtained in the boilers and in the consumer conduit while at the same time a large pressure drop in the motor is possible.

The pressure in the accumulator may vary between the pressure of conduit 18 which may, for example be 20 lbs. gage to the pressure of conduit 11 which may, for example, be 150 lbs. gage. The pressure in the accumulator is in proportion to the amount of steam stored. Despite the great variations of the accumulator the back pressure of the motor will be constant at 20 lbs. gage.

Conduit 28 with reducing valve 29 therein is normally inoperative and comes in operation only when, as might infrequently occur, the accumulator becomes fully discharged when valve 29 opens to admit high pressure steam direct to the low pressure consumers, so that steam will not wholly be cut off from the low pressure consumers.

S_1 represents a speed governor operating to cut down the supply of steam to the turbine in case the speed should for some reason unduly rise above normal.

Valve 27 not alone serves the purpose of acting as an auxiliary to valve 26 in operation but also maintains a constant boiler pressure, preventing the turbine from sucking too much steam from the boilers which would have deleterious effects on the boiler.

While the drawing has been executed in a manner to make the invention clear to those skilled in the art, only so much has been shown as is necessary to a full under-

standing of the invention, many parts, necessary or desirable being omitted for sake of clearness. The parts may be changed within the scope of the invention. The valves are only diagrammatically illustrated, it being understood that any valves performing the functions ascribed to those illustrated may be used.

Fig. 2 shows a plant similar in all respects to Fig. 1 except that high pressure consumers 30 are shown as supplied with steam ahead of valve 27. The operation of this plant is the same as that of Fig. 1. The valve 27 serves the additional purpose here that it maintains a constant pressure for the high pressure consumers.

In operation, suppose the pressure in high pressure line 11 rises somewhat due for example to decreased consumption of the high pressure consumers. The increased pressure operates to increase the opening of the valve 27, so that more steam flows through the turbine. If then there is too much steam in conduit 18, the pressure therein will rise and the opening through valve 26 will be increased. This in turn decreases the pressure in conduit 11, whereby valve 27 is closed somewhat, and the plant brought into a state of equilibrium.

Equalization is brought about in the reverse manner, if the pressure in conduit 11 should fall, the operation of the plant being readily apparent.

Fig. 3 shows a plant wherein a single extraction condensing turbine is used. In this case it is not necessary that the electric generator driven by the turbine be coupled in parallel with other electric generators. In this case the turbine is regulated so that it produces the exact amount of electrical energy needed in the circuit 15. 31 represents the condenser and 32 represents a speed responsive device controlling valve 33 and operating to control the supply of steam to the low pressure stages of the turbine at normal speed.

In operation, suppose the consumption of electrical energy increases, the number of revolutions of the turbo-generator set will then decrease somewhat and the normally operating speed responsive governor 32 will operate to increase the flow of steam to the low pressure section I of the turbine. Upon opening of the valve 33 the turbine would speed up so that the speed of the generator is constant, but this causes drop of pressure in the low pressure line 18. A drop of pressure in conduit 18 may operate as in previously described modifications to decrease the flow of steam through the valve 26, which in turn causes an increase of pressure in conduit 11. Increase of pressure in conduit 11 causes an increased flow of steam through valve 27, and high pressure section II so that the pressure in conduit 18 is re-

tained at a normal value. Thus a greater quantity of steam flows through the motor and less is by-passed to the accumulator.

If valve 26 is already closed when the pressure drops in conduit 18 valve 26 will open and admit steam to the low pressure consumers.

Further if the low pressure section of the turbine requires more steam than is supplied by the high pressure section, the deficiency will be supplied from the accumulator through conduits 21, 18 and 17.

Again, for example, suppose that the pressure in conduit 11 increases, valve 27 will then open wider and more steam will pass through the high pressure section H of the turbine. This would in most instances increase the speed of the turbine in which case governor 32 will operate to decrease the flow of steam through valve 33. If the low pressure consumers can not take care of the additional steam supply, valve 26 will be opened and valve 27 regulated so that again more steam is by-passed to the accumulator and less flows through the high pressure section of the motor.

Figs. 4 and 5 show a plant comprising a double extraction condensing turbine. The turbine comprises three sections, a high pressure section H an intermediate M and a low pressure section L. Both the high pressure section and the intermediate section are shown as being controlled by multiple nozzle regulation, otherwise known as partial regulation. This is indicated generally by reference characters 50 and 60 respectively. This type of regulation comprises a series of valves, each controlling a group of nozzles, some of which are indicated at 34, 35, 36 in Fig. 5, and operated successively by means of cams 37 attached to a rocker shaft 38 and actuating rocker arms 39 which operate the valves.

This type of regulation has distinct advantages over the single throttling valve since there is no appreciable drop of pressure through the valves of the partial regulation and thus the initial pressure of the turbine stage is maintained high and constant, a factor of great advantage in turbine efficiency.

The regulation of the turbine shown in Figs. 4 and 5 may be briefly summarized as follows:

The low pressure stages L are controlled by speed at normal values of the same. The intermediate stages M are controlled by the pressure ahead of the same, that is in the first supply chamber, by high value of speed and by low value of speed. The high pressure wheel is controlled by pressure ahead of the same, in the instance shown by boiler pressure and by high and low values of speed.

The structure will be described more in detail along with the description of operation.

Steam is supplied as previously, from a source of steam supply 10 and enters conduit 40 which supplies steam to the motor H M L. While I have shown a turbine as the motor, since this is the most practical, it will be understood that other types of consumers may be used. High pressure consumers 41 may or may not be connected to receive steam from conduit 40, depending on the design of the particular plant. Steam after passing through the high pressure stage H enters supply chamber 42 to which is connected extraction conduit 43 tapping steam into conduit 44, here shown as a digester line supplying steam to digesters 45. Conduit 44 corresponds somewhat to conduit 11 of the previous modifications since, as will be seen, if the boilers were connected to conduit 44 and the high pressure wheel H omitted from the turbine the plant is the same as that of Fig. 3. The steam supply to the intermediate stage M from the first supply chamber 42 is controlled by valves 60 and the steam after passing through the intermediate stages enters the second supply chamber 47 to which is connected extraction conduit 17 tapping steam into low pressure conduit 18 from which low pressure consumers as, for example the drying cylinders of paper machines 19, are connected. 21, as before, represents the accumulator conduit to which accumulator 22 is connected. Between conduits 44 and 21 extend the two conduits 20 and 28 containing the valves 26 and 29, which in practice are united into one conduit controlled by one valve responsive to a plurality of impulses according to the disclosure in patent application Ser. No. 604,111 filed Nov. 29, 1922, Patent No. 1,527,275, this construction being however, too detailed to show in this application and being such that one skilled in the art can apply the same to the present showing with proper results. In the present application I am describing the valves as separate although they may be either separate or combined. Regulating member 29 operates as in the previous modifications, being normally inoperative, and operating to admit steam from conduit 44 to conduits 21 and 18 when the accumulator is discharged. Regulating member 26, as previously, controls the flow of steam parallel to one or more motors, in this figure the motors being the intermediate and low pressure stages M and L. Reducing valve 25 is placed between conduits 18 and 21 and conduits 20 and 17 are so related to these conduits that conduit 20 is connected to the low pressure conduit 18-21 ahead of reducing valve 25

and conduit 17 behind valve 25, whereby the steam in supply chamber 47 is substantially the same as in conduit 18.

The regulation is such that a constant pressure is maintained in conduits 18, 40 and 44 and consequently in supply chambers 42 and 47. With a constant vacuum in condenser 31, it is thus seen that all turbine pressures are kept constant whereby the utmost efficiency of the turbine may be obtained while, at the same time the plant has all the well known advantages of the Ruths type of accumulator, including constant steam generation and ability to supply large momentary peaks.

If, for example, a peak occurs in conduit 44, say, for example, in a digester room, the pressure decreases momentarily in supply chamber 42. Pressure in chamber 42 then acts through pipe 48 to operate piston 49 which, through the agency of slide valve S_2 and other mechanism known per se operates to close some or all of the valves of regulator 60 so that less steam passes to the intermediate stages of the turbine and the pressure is maintained substantially constant in chamber 42. By known regulation this can be accomplished to within a variation of one pound pressure. The decrease in steam supply to intermediate stages M would probably in most cases lead to decrease the speed of the turbine whereby speed governor 50 will through rods 51, 52 and 53 and crank arms 54 and 55 cause valve 56 to increase its opening thereby admitting more steam to low pressure stage L. If this abstraction of steam from supply chamber 47 causes a decrease of pressure in conduit 18 below normal, it being assumed that valve 26 is closed, valve 25 will open and admit steam from the accumulator to conduit 18.

Suppose the pressure rises in conduit 40. The increasing pressure will act through conduit 57 to move piston 58 downwardly causing a movement of slide valve S_1 to change the liquid supply to servo-motor K which rotates rocker shaft 38 in clockwise direction so that more admission valves are opened and more steam passes through the high pressure stage H. With the resultant increase of pressure in supply chamber 42 and due to the increased flow through high pressure stage H, there occurs simultaneously an increased supply of steam through the intermediate section M and decreasing of opening of valve 56 due to mechanisms 60 and 50 in manner above described. This in turn increases the pressure in supply chamber 47 whereby the pressure in conduits 17 and 18 likewise rises, provided, of course, that the low pressure consumers do not simultaneously increase their steam demand so that the pressure remains normal. With an unchanged condition of consumption in

the low pressure conduits increased pressure in conduit 18 occurs which causes a movement of regulating member 26 to cause a greater flow of steam through conduit 20 to the accumulator. The pressure in supply chamber 42 then lowers which causes a decrease of steam passing through the intermediate stages and thus the flow of steam is shifted from the lower pressure extraction conduit to the higher and the load must consequently again shift back to the low pressure stages. The surplus of steam is thus mechanically sent into the accumulator. Although in following the stages through it seems that the many steps might cause lag in operation, the action is in practice practically instantaneous as has been demonstrated by an actual construction made according to this plan. It is not to be expected that variations will occur in the conduit 40 when no consumer is thereto attached, but the variations occur further down in the system where the regulation requires fewer steps.

The speed responsive device also operates at high and low values of speed as follows:

If the speed increases to such an extent that valve 56 is completely closed and the speed is still too high the stops 70 on rods 75 and 76 engage the respective levers 77 and 78 which control movement of slide valves S_1 and S_2 , and operate to close valves 50 and 60. On the other hand, if the speed of the turbine decreases to an excessively low value the stops 71 on rods 75 and 76 will be engaged to open valves 50 and 60.

From the above description it is evident that wherever fluctuations occur they will be automatically equalized and the turbine can have an expansion all the way down to the low pressure consumers at all times and is independent of variations of pressure occurring in the accumulator which may be very great.

What we claim is:

1. In a steam plant, a primary source of steam supply, a motor, a secondary source of steam supply, a consumer, a conduit to lead steam from said motor to said consumer, a conduit to lead steam from said secondary source of steam supply to said consumer, means to conduct steam in a path parallel to said motor from said primary source of steam supply to the second mentioned conduit and means to control the flow through the parallel path operated by changes of pressure in the first mentioned conduit.

2. In a steam plant in combination, a steam generator, a turbine of the double extraction type connected to receive steam from said generator, said turbine comprising a high pressure section, an intermediate pressure section and a low pressure section,

automatically operating pressure responsive means to control the supply of steam to said turbine, an intermediate pressure conduit, a first extraction conduit connected 5 to receive steam from said high pressure section and deliver the same to said intermediate pressure conduit, a consumer connected to receive steam from said intermediate pressure conduit, a low pressure conduit, a second extraction conduit connected 10 to receive steam from said intermediate pressure section and deliver the same to said low pressure conduit, a consumer connected to receive steam from said low pressure conduit, an accumulator, an accumulator conduit connected therewith, a reducing valve receiving steam from said accumulator conduit and delivering steam to said low pressure conduit, a connecting conduit extending 15 between said intermediate pressure conduit and said accumulator conduit and a valve in said connecting conduit operated by the pressure in the second extraction conduit and adapted to open when the last 20 mentioned pressure rises above a predetermined value.

3. In a steam plant, in combination, a source of steam, an extraction motor adapted 30 to receive steam therefrom, a low pressure conduit, an extraction conduit connected to receive steam from said motor and deliver the same to said low pressure conduit, a consumer connected to receive steam from said low pressure conduit, an accumulator, an accumulator conduit connected therewith, a reducing valve connected to receive steam from said accumulator conduit and deliver the same to said low pressure conduit, a conduit leading steam from 35 said source of steam to said accumulator and means to control the flow of steam through the last mentioned conduit in response to pressure in said extraction conduit.

4. In a steam plant, in combination, a steam generator, a consumer, adapted to receive steam therefrom, a low pressure conduit, a bleeder conduit leading from said consumer to said low pressure conduit, a consumer adapted to receive steam from said 45 low pressure conduit, an accumulator, a conduit adapted to lead steam from said accumulator to said low pressure conduit, a reducing valve to control the flow of steam through the last mentioned conduit, a conduit leading steam from said generator to said accumulator, a valve in the last mentioned conduit and means to control said valve operated in response to pressure in said bleeder conduit.

5. In a steam plant, in combination, a steam generator, a consumer, two parallel paths for steam from said generator to said consumer, the one path containing a reducing valve and having an accumulator connected thereto between said reducing valve

and said generator, a motor in the other path and control mechanism controlling the flow of steam from said generator to said accumulator and operated in response to pressure in the path containing the motor. 70

6. In a steam plant, in combination, a steam generator, a steam conduit system connected therewith, an accumulator, in said system, a consumer in said system, a conduit extending between said accumulator and said consumer, a reducing valve in said conduit, a motor in said conduit system, a connection between said motor and said conduit having a point of connection with said conduit such that said reducing valve lies between said 80 point of connection and said accumulator, a conduit leading steam from said generator to said accumulator, a valve in the last mentioned conduit and means to operate said valve responsive to changes of pressure in 85 said connection.

7. In a steam plant, in combination, a primary source of steam supply, a consumer adapted to receive steam therefrom, a low pressure conduit, a bleeder conduit leading 90 from said consumer to said low pressure conduit, a consumer adapted to receive steam from said low pressure conduit, a secondary source of steam supply, a secondary supply conduit adapted to conduct steam from said secondary source of steam supply to said low pressure conduit, a reducing valve to control flow of steam from said secondary supply conduit to said low pressure conduit, a conduit leading steam from 95 said primary source of steam supply to said secondary supply conduit, a valve in the last mentioned conduit and means to control said valve in response to pressure in said bleeder conduit. 100

8. In a steam plant, in combination, a steam generator, a high pressure conduit connected to receive steam from said generator, a consumer connected to said high pressure conduit, a motor connected to receive steam from said generator, a low pressure conduit, a conduit connected to receive steam from said motor and deliver the same to said low pressure conduit, an accumulator, an accumulator conduit connected therewith, a reducing valve receiving steam from said accumulator conduit and delivering the same to said low pressure conduit, means to conduct steam from said generator to said accumulator and a valve controlling the last mentioned means and operated by the pressure in the conduit receiving steam from the motor. 110

9. In a steam plant, in combination, a source of steam, a motor connected to receive steam from said source, regulating means to control the flow of steam to said motor operated by the pressure of the steam supplied thereto, a low pressure con- 120

duit, a connection for flow of steam from said motor to said low pressure conduit, a consumer connected to receive steam from said low pressure conduit, an accumulator, an accumulator conduit connected therewith, a reducing valve receiving steam from said accumulator conduit and delivering the same to said low pressure conduit, means to conduct steam from said source of steam said accumulator parallel to said motor ¹⁰ and regulating means controlling the last mentioned means and operated in response to pressure in said connection.

In testimony whereof we hereunto affix our signatures.

JOHANNES KARL RUTHS.
NILS PERSSON.
